(57) **CLAIM**

The ornamental design for a display screen with graphical user interface for stringing equipment, as shown and described.

DESCRIPTION

FIG. 1 is a front view of a display screen with graphical user interface for stringing equipment showing a first embodiment of the new design; and, FIG. 2 is a second embodiment thereof.

The outermost broken line illustrates a display screen and forms no part of the claimed design. All other broken lines in the drawings are included for the purpose of illustrating portions of the graphical user interface that form no part of the claimed design.

1 Claim, 2 Drawing Sheets
